[57] **CLAIM**

The ornamental design for a neon tube assembly with a transparent housing, as shown and described.

DESCRIPTION

FIG. 1 is a perspective view of a neon tube assembly with a transparent housing showing my new design; FIG. 2 is a top plan view thereof, the bottom being plain and unornamented;

FIG. 3 is a side elevational view thereof;

FIG. 4 is an elevational view of the other side thereof;

FIG. 5 is an end elevational view thereof; and,

FIG. 6 is an elevational view of the other end thereof.

FIG. 1

FIG. 2

FIG. 3

FIG. 4

FIG. 5

FIG. 6
